UNITED STATES PATENT OFFICE.

WILLIAM S. WOOD, OF NEW YORK, N. Y., ASSIGNOR TO WILLIAM M. RAYMOND & CO., OF SAME PLACE.

IMPROVEMENT IN SHEET-METAL COFFINS.

Specification forming part of Letters Patent No. 134,182, dated December 24, 1872.

To all whom it may concern:

Be it known that I, WILLIAM S. WOOD, of New York city, have invented an Improvement in Sheet-Metal Coffins, of which the following is a specification:

As a new article of manufacture my invention consists of a sheet-metal coffin, the sides, ends, and bottom of which are composed of a single sheet of metal. It is found necessary, in the manufacture of this style of coffins, to panel or emboss said parts; this process furnishing the lightest, cheapest, and most durable method of strengthening as well as ornamenting them. Heretofore these parts have been paneled or embossed in separate pieces, and then united, by brazing, riveting, or otherwise, to form the body of the coffin, involving greater delay in construction, and presenting a greater number of joints, thus weakening the structure, and also increasing the difficulty and expense of rendering it air-tight.

Not only does my improved method of constructing the body of a sheet-metal coffin diminish the number of joints, thus rendering the structure more nearly air-tight and giving increased strength with the same weight of metal, but it affords increased facilities for embossing the parts, thus materially lessening the cost of the structure, as I propose to emboss the single sheet of metal used at one impression in a pair of dies constructed for that purpose.

As a first step in the construction of a coffin in accordance with my invention, I cut, from a single sheet, a skeleton form, of such shape as would be obtained were the sides and ends of a coffin turned outward to a plane with the bottom thereof.

Figure 1 represents such a form, with one style of embossing; and Fig. 2 shows the body of a coffin completed, which consists of the bottom A, the sides B B, and the ends C C, composed of a single sheet of metal, as stated; the metallic rim D, resting on the horizontal flange E, formed on the upper edge of the sheet in the process of embossing, the outer edge of which flange is turned upward to conceal the rim; the handle-plates G on the interior; the ribs H, as an additional support to the sides; and the panels I.

Instead of turning upward the outer edge of the horizontal flange on the body of the coffin as a mode of concealing the metallic rim D, it is plain that the edge of the corresponding flange upon the cover of the coffin may be turned downward.

The main function of the rim D is to give the rigidity to the structure, and at the same time to furnish the necessary support to the screws used to connect the cover with the body of the coffin. By constructing the two flanges as described, and placing the rim between them, this end is secured without exposing the rim to view and thereby marring the external appearance of the casket, as will be the case when the strengthening device is placed underneath the flange formed on the upper edge of the body. The cement used for making the joint between the cover and the body of the casket air-tight will, of course, be disposed upon and around the rim D.

The second step in my invention is to suitably emboss these parts, as above described; after which they are ready to be formed into the body of the coffin by turning them up, as indicated by the dotted lines a. This is most conveniently effected by means of a form-block, over which the coffin is shaped. The corner-irons F, curved or angular, as the shape of the coffin may demand, are then fitted in the corners as a means of strengthening the joints and rendering them air-tight by brazing the sides and ends firmly thereto. The handle-plates G, to which the handles are secured by bolts, rivets, or their equivalents, are placed on the interior of the sides to distribute the strain on the handle over a larger surface of the sides, and thereby strengthen them.

The L-shaped ribs H, two or more in number, as may be required, are secured on the interior to the sides and bottom, to prevent bulging when a heavy body is supported within.

From the above description of the essential features of my invention it is evident that various modifications in form and in detail of construction may be devised. Hence I do not limit myself to any particular modification of either; but—

I claim—

1. A sheet-metal coffin, the sides, ends, and bottom of which are composed of a single sheet of metal.

2. The combination of the metallic rim D with the flange formed on the upper edge of the body of the coffin, the rim itself being concealed, substantially as described, by the up-

turned edge of this flange, or by its equivalent, a depending flange formed on the cover.

3. The handle-plates on the interior of a sheet-metal coffin, substantially as described.

WILLIAM S. WOOD.
